(57) **CLAIM**

The ornamental design for lighting devices for vehicles, as shown and described in FIGS. 1-18.

DESCRIPTION

FIG. 1 is a perspective view illustrating a reflector and an associated bezel in a housing with the housing not forming part of the design and phantomed to show an environment in which the reflector is positioned;

FIG. 2 is a right side view, with the left side view being substantially a mirror image;

FIG. 3 is a front view of the reflector shown in FIG. 1;

FIG. 4 is a top view of the reflector shown in FIG. 1;

FIG. 5 is a bottom view of the reflector shown in FIG. 1;

FIG. 6 is a rear view of the reflector shown in FIG. 1;

FIG. 7 is a sectional view taken along line 7—7 in FIG. 3;

FIG. 8 is a sectional view taken along the line 8—8 in FIG. 3;

FIG. 9 is a sectional view taken along the line 9—9 in FIG. 3;

FIG. 10 is a view of an embodiment similar to the embodiments of FIGS. 1-8, except that the surface of the inner rim is black;

FIG. 11 is a right side view of the embodiment of FIG. 10, with the left side view being substantially a mirror image;

FIG. 12 is a front view of the reflector shown in FIG. 10;

FIG. 13 is a top view of the reflector shown in FIG. 10;

FIG. 14 is a bottom view of the reflector shown in FIG. 10;

FIG. 15 is a rear view of the reflector shown in FIG. 10;

FIG. 16 is a sectional view taken along line 16—16 in FIG. 12;

FIG. 17 is a sectional view taken along the line 17—17 in FIG. 12; and,

FIG. 18 is a sectional view taken along the line 18—18 in FIG. 12.
